UNITED STATES PATENT OFFICE.

JOSEPH BILLINGHAM AND CHARLES F. KAHLER, OF SCHENECTADY, NEW YORK.
DRIFTING-VALVE FOR LOCOMOTIVES.

1,112,109.

Specification of Letters Patent. Patented Sept. 29, 1914.

Application filed April 24, 1914. Serial No. 834,054.

To all whom it may concern:

Be it known that we, JOSEPH BILLINGHAM and CHARLES F. KAHLER, both of Schenectady, in the county of Schenectady and State of New York, have invented a certain new and useful Improvement in Drifting-Valves for Locomotives, of which improvement the following is a specification.

The object of our invention is to provide effective and automatically operable means, of ready applicability in locomotive engines of the various present standard constructions, and particularly desirable for application in those using superheated steam, whereby by the formation of a vacuum in the cylinders, when the locomotive is "drifting," or running with throttle closed, will be prevented, thereby preventing dust and cinders from being drawn into the cylinders, as well as for insuring proper lubrication of the cylinders and preventing carbonization of oil therein, by causing a limited quantity of steam to be continuously passed through them during the running condition above stated.

The improvement claimed is hereinafter fully set forth.

In the accompanying drawings: Figure 1 is a diagrammatic side view of a locomotive engine, illustrating an application of our invention; Fig. 2, a vertical central section, on an enlarged scale, through the admission valve mechanism; Fig. 3, a similar section through the vacuum piston mechanism; and, Fig. 4, a side view of the cylinder and valve chest, illustrating a structural modification.

Our invention is herein exemplified as applied in a Pacific type locomotive engine of standard design, in which the supply and exhaust of steam to and from the cylinders, 1, are controlled by distribution valves which are reciprocated in valve chests, 2, located above the cylinders, in the ordinary manner.

In the practice of our invention, we provide a vacuum piston chest or casing, 3, which is most conveniently located on one of the valve chests, 2, in the position ordinarily occupied by the relief valve, the casing communicating, at its bottom, with the space within the valve chest on the admission side of the distribution valve, and being connected to the valve chest by a screw shank, 3^a, or in any other suitable known manner. An open-topped piston chamber, 3^b, is formed in the casing, 3, adjacent to a detachable cap, 3^c, which closes the top of the casing, and a

central passage, 3^d, of substantially smaller diameter than the piston chamber, extends downwardly therefrom in the casing, its lower end being closed by a screw plug, 3^e. An air port, 3^f, extends from the passage, 3^d, near its upper end, to the atmosphere; an exhaust port, 3^g, extends from the passage to the atmosphere, a short distance above the lower end of the passage; and a drain port, 3^h, leads out of the passage at or immediately adjoining its lower end. A pressure inlet port, 3ⁱ, leads into the passage, 3^d, and a pressure outlet port, 3^j, leads out of said passage, below the pressure inlet port.

A fluid pressure supply pipe, 4, leads from any suitable source of fluid pressure supply, which, in the specific embodiment of our invention herein exemplified, is the main reservoir, 5, of the brake apparatus of the locomotive, to a connection with the pressure inlet port, 3ⁱ, and a fluid pressure delivery pipe, 6, leads from a connection with the pressure outlet port, 3^j, to an admission valve mechanism, which is located in the cab of the locomotive, and will be presently described. A properly packed piston, 7, is fitted in the piston chamber, 3^b, and is secured on a piston stem, 7^a, which extends downwardly in the central passage, 3^d, of the casing, and carries three pistons, 8, 9, and 10, fitting the passage, 3^d, and making tight joints therewith by suitable packing. In the normal or inactive position of the parts, the piston, 8, stands between the piston chamber and the fluid pressure supply pipe; the piston, 9, between the fluid pressure supply pipe and the fluid pressure delivery pipe; and the piston, 10, below, and clear of, the exhaust port, 3^g.

The fluid pressure supply pipe, 4, may, as shown in dotted lines in Fig. 1, instead of being connected to the main air reservoir, 5, as shown, lead from any suitable location in the steam space of the boiler; and, in such case, is preferably connected to the small steam dome or turret, 15, hereinafter specified, and controlled by a manually operable cock or valve adjacent thereto. Either compressed air or steam may, without departure from the spirit and operative principle of our invention, be used for actuating the motor piston of the admission or drifting valve proper hereinafter described.

The admission valve mechanism proper is inclosed in a chest or casing, 11, which is

preferably, as shown, located in the cab of the locomotive, and comprises a lower piston chamber, 11^a, to the removable bottom plate, 11^b, of which, the fluid pressure delivery pipe, 6, leading from the vacuum piston casting, 3, before described, is connected, and an upper valve chamber, 11^b, which communicates with the piston chamber through a central passage, and is closed at top by a removable cap, 11^c. A partition, 11^d, extends across the valve chamber, and has formed within it a central opening which is controlled by a steam admission valve, 12, seated in the partition, around the opening thereof, and located above a stem, 12^a, which extends into the piston chamber, 11^a, within which it carries a properly packed piston, 13, of substantially larger diameter than the valve, 12, and fitting said chamber. A small piston, 13^a, on the stem, 12^a, fits in the passage between the valve and piston chambers, and prevents flow of steam from the former to the latter. The valve chamber, 11^b, is connected, above the admission valve, with the steam space of the locomotive boiler, by a pipe, 14, which preferably leads to a turret or small steam dome, 15, on the boiler, and is controlled by a manually operable valve, 16. A pipe, 17, leads from the valve chamber, below the admission valve, to each of the distribution valve chests, 2, to which it is connected, on the admission side of the valves, by a T and branches, as shown in Fig. 1. A check or non-return valve, 18, of ordinary construction, is located in the pipe, 17, to prevent backward flow of steam to the valve chamber, 11^b.

In the operation of the mechanism above described, the steam supply valve, 16, having been opened, and the locomotive running under steam, i. e., with its throttle valve open, the admission valve, 12, is held to its seat by the steam pressure above it, and the pistons, 7, 8, 9, and 10, of the vacuum piston mechanism, being subject to valve chest pressure, acting on the upper side of the piston, 7, remain in the ordinary normally seated positions shown in Fig. 3. When the locomotive is "drifting" or running with its throttle closed, a partial vacuum will, by the reciprocation of the pistons in the cylinders, be formed therein, in the distribution valve chests on the admission side of the valves, and in the steam supply connections leading from the throttle valve to the distribution valve chests. The pressure previously acting on the upper side of the piston, 7, will be correspondingly reduced, and atmospheric pressure, acting on the lower side of said piston through the port, 3^c, will raise it, and the connected pistons, 8, 9, and 10 thereby bringing the fluid pressure supply pipe, 4, into communication with the fluid pressure delivery pipe, 6.

The pressure delivered from said pipe to the

lower side of the piston, 13, of the admission valve mechanism, will raise said piston, thereby unseating the admission valve, 12, and admitting a limited volume of steam through the pipes, 14 and 17, to the distribution valve chests and the cylinders. This admission of steam will continue during the drifting of the locomotive, thereby counteracting the tendency to the formation of a vacuum in the cylinders, and also, which is of material importance, effecting the lubrication of the cylinders by the admission of steam and of the oil which it carries with it from the lubricating pipes, which are located adjacent to the inlets of the branches 8 of the pipe, 17.

It is, of course, particularly desirable, if not absolutely essential to conditions of safety, that the admission of steam to the cylinders through a conduit independent of that which is controlled by the throttle valve, which has been effected while "drifting," should be stopped when the throttle valve is closed and the locomotive is standing. This cessation of independent steam admission is, under the condition last stated, automatically effected, in the operation of our improvement, by the building up or increase of pressure in the cylinders, due to the admission of steam thereto through the pipe, 17. As soon as the cylinder pressure exceeds that of the atmosphere, the piston, 7, will be depressed, the air below it being exhausted through the port, 3^c; the piston, 9, will cut off communication between the fluid pressure supply pipe, 4, and the fluid pressure delivery pipe, 6; and the fluid pressure in the latter pipe will be exhausted therefrom through the port, 3^c. The pressure on the lower side of the piston, 13, of the admission valve mechanism, being thereby relieved, the steam pressure on the upper side of the admission valve, 12, will force it to its seat, and the supply of steam to the cylinders will be cut off, and remain cut off, while the locomotive is standing.

Experience with superheated steam locomotives has developed that difficulty has been experienced by the carbonizing of oil in the cylinders, and that, when drifting, there is a gummy and sticky deposit of oil on the cylinders, and that the adhesion, to this gummy deposit, of dirt drawn into the cylinders when the engine is drifting to any extent with throttle entirely closed, converts it into a composition which rapidly wears away the packing rings and piston heads. It has also been found in practice that a constant small admission of steam to the cylinders tends to insure proper lubrication and prevent the carbonizing of the oil, and that good results have been obtained by keeping the throttle slightly open when the engine was drifting. The objections to this practice are, however, manifest to those

skilled in the operation of locomotives, and it will be equally obvious that these will be avoided by the application of our invention, in the operation of which steam is 5 automatically admitted to the valve chests and cylinders, entirely independently of the throttle valve, when the engine is "drifting," and such independent admission of steam is automatically stopped when the engine 10 is running under steam or is standing.

While, in the specific structural embodiment of our invention herein set forth, the steam which is independently supplied by the admission valve is delivered therefrom 15 into the distribution valve chests, it will be obvious that, if preferred, the pipes through which such independent supply of steam is effected may be connected directly to the cylinders, as shown in Fig. 4. The manner 20 of operation and result attained by our invention are the same whether the admission be direct, or indirectly through the valve chests as set forth, and the steam supply connections to the cylinders are the mechanical 25 equivalents of similar connections to the valve chests. The adoption of one or the other location of connection is a matter within the discretion and ordinary skill of the constructor, and the specific location is 30 not an essential of our invention.

The vacuum piston mechanism hereinbefore set forth, is not, in and of itself, claimed as of our present invention, and constitutes the subject matter of a divisional 35 application filed July 17, 1914, Ser. No. 851,442.

We claim as our invention and desire to secure by Letters Patent:—

1. In a drifting valve mechanism for locomotives, the combination of means for controlling the supply of steam from a boiler to a distribution valve chest, independently of the main steam supply pipe, a source of fluid pressure supply independent of said 45 pipe, and mechanism, actuated by variation of valve chest pressure, for automatically governing the application of pressure from said independent source to said steam supply controlling means.

2. In a drifting valve mechanism for locomotives, the combination of a valve controlling the supply of steam from a boiler to a distribution valve chest, independently of the main steam supply pipe, means for actuating said valve by the application, in the 55

opposite direction, of boiler supply steam and of fluid pressure from a source independent of the main steam supply pipe, and mechanism, actuated by differences of valve chest pressure, for controlling the supply of fluid pressure from the independent source to the valve actuating means.

3. In a drifting valve mechanism for locomotives, the combination of a valve controlling the supply of steam from a boiler to a distribution valve chest, independently of the main steam supply pipe, means for unseating said valve by fluid pressure from a source independent of said pipe, and mechanism, actuated by a reduction of valve chest 70 pressure, for supplying fluid pressure to said unseating means.

4. In a drifting valve mechanism for locomotives, the combination of an admission valve controlling the supply of steam from a boiler to a distribution valve chest, independently of the main steam supply pipe, an actuating piston, of larger diameter than said valve and connected thereto, a source of fluid pressure supply independent of the main steam supply pipe, and mechanism, actuated by differences of valve chest pressure, for controlling the supply of fluid pressure from the independent source to the actuating piston.

5. In a drifting valve mechanism for locomotives, the combination of an admission valve mechanism comprising an inclosing casing, a valve fitted therein and controlling communication between a boiler supply steam pipe and a delivery steam pipe leading to a distribution valve chest, and a piston of larger diameter connected to the valve; a source of fluid pressure independent of the main steam supply pipe; and a vacuum piston mechanism comprising an inclosing casing, a piston therein subject on its opposite sides to atmospheric and distribution valve chest pressure, respectively, and pistons of smaller diameter connected to said last specified piston and controlling communication between the independent source of fluid pressure and the piston of the admission valve mechanism.
